INTERNAL COMBUSTION ENGINE

Roger K. Lee, Highland Park, Mich., assignor to
 Chrysler Corporation, Detroit, Mich., a corpora-
 tion of Delaware

Application June 30, 1934, Serial No. 733,200

14 Claims. (Cl. 123—55)

This invention relates to internal combustion engines and refers more particularly to improvements in engines of the type wherein the cylinders are arranged radially about the engine crank-shaft.

My invention is also particularly related to internal combustion engines of the positive valve operating type although in the broader aspects thereof many of the novel features of my invention are not necessarily limited to radial types of engines or to engines having positively operated valves.

It is an object of my invention to provide an improved valve operating mechanism which may be successfully operated at speeds materially higher than the usual speeds of conventional engines, used for driving motor vehicles, for example. While my improvements are not necessarily limited in their application to such high speed engines or to engines for driving motor vehicles, they are particularly adapted to such applications.

Another object of my invention is to provide improved valve operating means for radial engines wherein the timing of the valve operations will be maintained with improved precision, thereby resulting in greater engine efficiency, smoother engine operation, and adaptability to relatively high engine speeds.

A further object of my invention is to provide an improved valve operating means especially adapted for radial engines wherein a plurality of valve operating shafts are cooperatively associated with each other and simultaneously driven in an improved manner from the engine.

Another object of my invention is to provide an improved valve operating mechanism, especially of the positive operating type, wherein the valve operating arms are arranged in an improved manner with respect to the engine cylinders. Thus, I have provided a novel arrangement of pairs or groups of valve operating arms, the arms of each pair respectively actuating an intake and an exhaust valve of adjacent cylinders.

An additional object of my invention resides in the provision of improved means for driving the valve shafts wherein the crankshaft drives the valve shafts but the crankshaft and valve driving mechanism are free to deflect relatively to each other. This feature of my invention provides improvements especially in connection with engines having cantilever crank pins, my invention making it possible in an improved manner to utilize a crank pin of this type to drive

the valve operating mechanism without influence from crank pin deflections.

A further object of my invention is to provide an improved lubricating means or system for the valve operating shafts, the lubricating means preferably also being extended to provide lubrication under pressure for the valve shaft driving mechanism, connecting rod bearings, and crank pin.

Another object of my invention is to provide improved means for operating the engine accessories and for mounting and arranging the accessories in a simplified manner by utilizing existing driving mechanism in the engine. Thus, I have provided for driving the cooling system fan, distributor, water pump, and oil pump from the crankshaft through the intermediary of valve operating or driving shafts which are preferably grouped about one end of the crankshaft.

An additional object of my invention is to provide an improved cooling means or cooling fluid circulating system for an engine, my cooling system being particularly adapted to radial engines.

A further object of my invention is to provide a simplified, light weight engine structure of the radial type.

Among further features of my invention is the provision of a unitary combined fuel mixture intake and cooling fluid manifold structure associated with the various engine cylinders; the provision of an improved intake manifold and fuel mixture supply means for the engine; the provision of means for supporting the valve operating levers from the aforesaid manifold structure; and the provision of improved lubrication means for the valve shafts and other mechanism drivably associated therewith.

Further objects and advantages of my invention will be more apparent from the following detailed description of one illustrative embodiment thereof, reference being had to the accompanying drawings in which:

Fig. 1 is a sectional elevational view longitudinally through my engine, the section being taken along the line 1—1 of Fig. 2.

Fig. 2 is a front elevational view of my engine with parts thereof broken away to illustrate a typical cylinder and the valving mechanism associated therewith.

Fig. 3 is a sectional plan view through one of the cylinder heads as indicated by the line 3—3 of Fig. 2.

Fig. 4 is a sectional elevational view somewhat fragmentary and diagrammatic in form illustrating the arrangement of the valve operating shafts.

the section being taken along the line 4—4 of Fig. 1.

Fig. 5 is a sectional elevational view along the line 5—5 of Fig. 1.

5 Fig. 6 is a front elevational view of the combined intake manifold and cooling water manifold structure also illustrating the manner of support for one of the pairs or groups of valve operating levers.

10 Fig. 7 is a fragmentary top plan view partly in section of the structure shown in Fig. 6, the view being taken as indicated by the line 7—7 of Fig. 6.

15 Fig. 8 is a fragmentary side view of the structure shown in Fig. 6, the view being taken as indicated by the line 8—8 of Fig. 6.

Fig. 9 is a detail sectional view taken along the line 9—9 of Fig. 8.

20 Figs. 10 and 11 are detail views of the structure shown in Fig. 6, these views being respectively taken as indicated by the lines 10—10 and 11—11 of Fig. 6.

Fig. 12 is a detail sectional view taken along the line 12—12 of Fig. 10.

25 Fig. 13 is a detail sectional view taken along the line 13—13 of Fig. 11.

Fig. 14 is a detail sectional view taken along the line 14—14 of Fig. 1 illustrating the crank pin and connecting rod assembly.

30 Fig. 15 is a detail sectional elevational view taken along the line 15—15 of Fig. 1 illustrating my improved drive for the valve operating mechanism.

Referring to the drawings, it will be noted that 35 I have illustrated my improvements in an internal combustion engine of the six-cylinder radial water-cooled type. Engine speeds of 5,000 to even 10,000 R. P. M. are possible b. utilizing my inventions although it will be understood that such values of engine R. P. M. are cited herein for illustrative purposes in order to illustrate the unusual operating characteristics of my improvements and such values in practice may be varied as desired.

45 The engine includes a fixed crankcase structure 10 and radially disposed cylinders 11 secured in equiangular relation on said crankcase. The cylinders 11 may have any desired suitable construction, the novel cylinder structure illustrated in the drawings not forming a part of the subject-matter claimed in this application. According to the present embodiment of my invention each of the cylinders 11 is of the water-cooled type although many of the features of my invention which do not relate to the water-cooling system may be employed with air-cooled cylinders. Each cylinder has an inner sleeve 12 and an outer sleeve 13 maintained in concentric and spaced relation by a base member 14 and a top member 60 or cylinder head 15, these members being suitably bonded as by welding to the sleeves. The base members 14 are provided with flanges 16 shown in Fig. 2 by which adjacent cylinders may be secured to the crankcase by means of clamps 65 17 and bolts 18. The spaced concentric sleeves 12 and 13 provide water jacket spaces 18a between and around the cylinder walls, these jacket spaces communicating through ports 19 with water jacket spaces 20 provided in the cylinder heads 70 15.

Slidable within the inner sleeve 12 which constitutes the cylinder wall of each cylinder is a piston 21 which may be of any suitable construction and which does not in itself constitute a part 75 of my invention as claimed in this application.

The main portion of each connecting rod is indicated at 22 and may be tubular in form for lightness in weight, an annular bearing member 23 being permanently secured to each tubular rod portion 22, the bearing members being adapted to receive the crank pin of the engine.

5 The crankcase structure 10 comprises a central main body portion 24 having rear and front openings adapted to be closed by the covers, wall structures or end members 25 and 26. The parts 10 of the crankcase are preferably aluminum or similar light weight metal or alloy castings and the body portion 24 is provided with an annular series of cores indicated at 27 for the reception of the respective cylinder sleeves 12, and as indicated 15 at 28 in Fig. 4 for the accommodation of the pairs of cam-actuated valve operating arms which will be presently described in detail. The rear end member 25 of the crankcase structure is substantially bell-shaped and centrally apertured at the 20 smaller end 29 thereof for the reception of a crankshaft 30 shown in Fig. 1. Power taken from the crankshaft is adapted to drive the motor vehicle (not shown) or to operate such other machine or device as may be desired. This crankshaft is journaled in ball and race types of bearings 31 and 32 mounted in the crankcase and arranged adjacent the ends of the crankshaft, the bearing 31 being carried within the end 29 of member 25 and the bearing 32, which has a larger diameter than the bearing 31, being mounted in the transverse wall 33 secured by fasteners 34 between the forward end of the members 25 and the crankcase body portion 24.

35 The crankshaft 30 is provided with an enlargement 35 in which is journaled, eccentrically with respect to the axis of the crankshaft, a spindle 36 which projects forwardly beyond the end of the crankshaft and into the crankcase body portion 24 to provide a cantilever crank pin 31.

The spindle 36 is journaled intermediate its length by a roller bearing 38 arranged at the forward end of the enlarged portion 35 and by a ball and race type bearing 39 journaled in the rear end of spindle 36 at the rearwardly disposed end 45 of the enlargement 35 of the crankshaft. The spindle 36 is maintained in position within the bearings 38 and 39 by a shoulder 40 which abuts the forward face of the bearing 39 and by a nut 41 which will presently be more fully described. 50

The forwardly projecting end 37 of the spindle 36 forms the engine crank pin on which is journaled the annular bearing members 23 connected to the aforesaid connecting rod members 22. Referring also to Figs. 1 and 14 it will be noted that 55 the annular bearing members 23 in the present illustrated embodiment of my invention are arranged side by side with the axes of adjacent cylinders slightly spaced longitudinally of the crank pin 37 although the cylinder axes may be 60 positioned in a common plane if desired.

All of the bearing members 23 are directly journaled on the crank pin 37 which, in turn, is rotatably journaled relative to the crankshaft 30. The rear edge of the rearmost bearing member 65 23 abuts a shoulder 42 on the spindle 36 and in this manner the connecting rods are held assembled on the crank pin against displacement rearwardly.

A wall structure 43 extends transversely of the 70 crankcase structure 10 and is adapted, in conjunction with the end member 26, to provide a valve operating chamber 44 forwardly of or to the left of the wall 43 as viewed in Fig. 1. The dividing wall 43 separates the chambers 13 and 24 75

and thus prevents oil mist and particles of oil thrown about in chamber 73 from passing to chamber 24 whereby cylinders 12 are not excessively lubricated.

5 The valve operating mechanism which is located in the chamber 44 and which will be presently described in detail is driven from a driving shaft 45 which is co-axial with the crankshaft 30 and which is provided with a drive pinion 46. This shaft is rotatably journaled by a bearing 47 in the wall 43 and by a forward bearing 47^a carried by the end member 26, the shaft 45 having a portion thereof projecting rearwardly into the crankcase 24 for mounting a disc 48 adapted to 10 drive the shaft 45. This valve gear driving disc 48, as best seen in Figs. 1 and 15, is provided with an opening 49 adapted to receive a bushing 50, the bushing and disc being capable of a slight amount of relative rotational movement as will 15 be presently apparent. The bushing 50 has an opening 51 eccentric with the opening 49, the opening 51 being rotatably engaged by the forwardly projecting end of a driving pin 52, this pin being provided with a rearward enlarged portion 53 thereof fitting within the forwardly opening bore 54 of the crank pin 37.

The driving pin 52 is locked in place with the crank pin 37 by engagement of the diametrically spaced crank pin projections 55 which, as best seen in Fig. 14, fit into radially extending slots 56 formed in the front face portion of the crank pin 37. In order to clamp the driving pin 50 in position and also to maintain the connecting rod assembly against forward axial displacement on the crank pin I have provided the clamping rod 57 which extends axially through the bore 54 of the spindle 36 for threaded engagement at its forward end with the aforesaid drive pin portion 53, the rear end of the rod 57 extending rearwardly beyond the rear bearing 39 for receiving the aforesaid clamping nut 41 which reacts against the rear end face of the spindle 36 as seen in Fig. 1.

By reason of the eccentricity between the centers of the openings 49 and 51 of the bushing 50, it will be apparent that the disc 48 will not take any of the load of the crank pin 37, the disc 48 having only rotation with the crankshaft 30 since any tendency of the crank pin to load the disc 48 and shaft 45 will be compensated for by a slight rotative movement of the bushing 50 in the opening 49. Likewise it will be apparent that any deflection of the shaft 45 will not be transmitted to the crank pin, the bushing 50 in such instance having a slight rotative movement as aforesaid. It will be apparent that the bushing 50 may be rotated through an angle of 180° when the disc 48 is disconnected from the bushing, this rotation of the bushing providing a convenient means of changing the relative timing in the drive between the crank pin 37 and the shaft 45.

The shaft 45 has an axial oil-conducting passage 59 closed by a plug 60 at its crankcase end adjacent which the shaft is provided with a radial communicating passage 61 registering with a radial passage 62 in the disc 48. The supply of lubricating oil under pressure to shaft passage 59 will be presently described. The passage 62 registers with one of the passages 63 in the bushing 50 depending upon the position of adjustment of this bushing as aforesaid and the passage 63, in turn, registers with a radial passage 64 in the drive pin 52, the latter having an axial lubricant conducting passage 65 adapted to

conduct the lubricant to the aforesaid bore 54 of the crank pin 37 by reason of a further passage 66 shown in Figs. 1 and 14 as extending for the most part through the enlarged drive pin portion 53. The connecting rod bearings 23 are supplied with lubricant from the crank pin bore 54 by a series of radial conduits 67 through the crank pin at each rod bearing. Lubricant also travels through bore 54 and through the rear conduit 68 to lubricate the bearing 32.

5 A plurality of valve shafts or cam shafts 69, preferably six in number for a six-cylinder radial engine as illustrated, are journaled rearwardly by bearings 70 in the partition 43 and forwardly by bearings 71 in the end member 26. Each cam 15 shaft is provided with a gear 72 arranged in equiangular position relative to and about the axis of the shaft 45 and the crankshaft 30. The gears 72 are each of a diameter twice that of pinion 46 for the four-stroke cycle engine illustrated so 20 that each of the cam shafts 69 receives equal rotation in the same direction at one-half the speed of the crankshaft 30.

The arrangement of the valve shafts 69 in the valve shaft receiving chamber 73 formed by the 25 partition 43 and end member 26 is such that a line between the axes of two adjacent shafts will be bisected by a line normal thereto and passing through the common axis of rocking of a pair of valve operating bell crank levers 74 and 75. 30 These pairs of bell crank levers are each supported in the space provided between adjacent cylinders 11 and each lever 74 has an arm 74^a extending in the same direction generally circumferentially of the engine. Each arm 74^a is 35 fixed to the rear end of a sleeve shaft 76 which projects beyond the bearing therefor as shown in Fig. 7. This bearing has an inner portion 77 supported by the manifold structure 78 and projecting outwardly therefrom preferably as an integral portion of the manifold casting. The portions 77 of the sleeve bearings may slightly vary in length at different locations thereof around the manifold structure 78 as noted in Figs. 8, 10 and 11 in order to adapt the bearing portions to 40 different length sleeve shafts as will be presently apparent. Each bearing portion 77 has a bearing cap 79 removably secured thereto by fasteners 80.

Each sleeve 76 also projects forwardly of its 50 bearing to receive the outer end of an arm 83 which is fixed to the sleeve.

Each bell crank lever 75 has an arm 84 secured to the portion of a rocking sleeve shaft 85 which projects rearwardly beyond the sleeve 76. Each 55 shaft 85 extends forwardly through an associated sleeve 76 and is thereby journaled independently of the sleeve, the forwardly projecting end of each shaft 85 having fixed thereto the outer end of an arm 86.

It will be noted that the arms 84 of the bell crank levers 75 also extend in the same direction generally circumferentially of the engine but in the opposite direction to that of the arms 74^a of the bell crank levers. The other arms 83 and 86 65 of the bell crank levers 74 and 75 respectively extend inwardly in a general radial direction in pairs through the aforesaid openings 28 for operation by the cam shafts 69.

Each pair of bell crank levers 74 and 75 is 70 arranged so that the arm 74^a of lever 74 is adapted to positively operate the intake valve 87 of the adjacent cylinder in one direction of sequence (clockwise from each supporting sleeve 76 of the bell crank levers 74 as viewed in Fig. 2) while 75

each arm 84 of the bell crank levers 75 extends in the opposite direction for operating in a similar manner an exhaust valve 88 of the other cylinder adjacent each pair of bell crank levers. 5 Thus each pair of bell crank levers is arranged for operation between adjacent pairs of cylinders, these levers having oppositely extending arms respectively adapted to operate an intake and an exhaust valve of the adjacent cylinders. It will 10 also be noted that adjacent cylinders have their intake and exhaust valves arranged adjacent the space between the cylinders whereby the pair of bell crank levers occupying this space can be conveniently connected to these valves. 15 The intake and exhaust valves 87 and 88 for a typical cylinder are best illustrated in Figs. 2 and 3. Each cylinder head 15 is provided with a pair of outwardly extending circumferentially spaced valve guide brackets 89 and 90 respectively adapted to guide the stems 91 and 92 of the intake and exhaust valves 87 and 88 as best shown in Fig. 2. Each of the valve guide brackets has an opening 93 intermediate the length thereof for receiving the operating connection with the 20 respective bell crank lever arms 74^a and 75.

In Fig. 7 I have illustrated the operating connection between the arm 74^a and valve stem 91, it being understood that a similar operating connection is provided for operating the remaining 30 intake valves and also the exhaust valves of the various cylinders. Thus, the arm 74^a slidably and telescopically receives the arm extension 94, this extension rotatably journaling the arm 95 which has its axis at right angles to the common axis of the arm 74^a and the arm extension 94. The arm 95 has a bearing portion 96 threadedly receiving the intermediate threaded portion of the valve stem 91 whereby the valve 87 may be adjusted axially of the valve stem with respect to the arm 40 95. A locking member 97 shown in Fig. 2 is adapted to adjustably maintain the arm 95 connected with the valve stem 91. The valve stem has its outer end provided with a slot 98 to receive a screwdriver for facilitating the adjustment of 45 the valve stem axially with respect to the bearing 96 of the arm 95.

As the arm 74^a is given an oscillatory movement about the axis of its sleeve bearing 76 it will be apparent that the valve stem 91 will be 50 positively reciprocated to control the opening and closing of the valve 87, the arm extension 94 having a slight axial movement in and out with respect to the arm 74^a to compensate for the swinging movement of the arm 74^a. The arm 95 connected with the valve stem 91 will also have a slight rotative movement in the journal provided by the outer portion of the arm extension 94, the arm 95 moving up and down with the valve stem 91 within the opening 93 of the valve 55 stem guide bracket 89. A similar operating connection is provided as aforesaid for each of the operating arms 84 of the bell crank levers 75 for connection with the respective valve stems 92 of the exhaust valves 88.

60 Each cylinder head 15 is provided with a forwardly extending intake gas passage 99 and the oppositely or rearwardly extending exhaust gas passage 100 best shown in Fig. 3, these passages respectively opening at the sides of each cylinder 65 for communication with the intake and exhaust gas manifolds 101 and 102 for respectively conducting the usual intake gas mixture to the engine cylinders under control of the intake valves 87 and for conducting the exhaust gases from the 70 cylinders under control of the exhaust valves 88.

Each valve shaft 69 has four cams 103 secured by a key 104 to a sleeve 105, the latter being mounted as a unitary assembly on its associated valve shaft 69 and secured thereto by a key 106. These cams are arranged in pairs on each shaft, 5 one pair of cams being adapted to operate the intake and exhaust valves of adjacent cylinders as aforesaid while cooperating with one pair of cams on an adjacent shaft, the other pair of cams being adapted to cooperate with the other 10 pair of cams on the other adjacent shaft to operate the remaining valve of one of said adjacent cylinders and also a valve of the next adjacent cylinder. In other words, each valve shaft with its two pairs of cams cooperates with one pair 15 of cams on each valve shaft adjacent thereto to operate the sets of intake and exhaust valves of two cylinders as will be apparent from Fig. 2.

Each cam on the shafts 69 cooperates with a suitably shaped cam provided upon an adjacent 20 shaft so that both cams remain in contact with the inner ends 107 of the arms 83 or 88. These cams and inner arm ends are so shaped that when the cam on one shaft begins to lift the arm end 107, the cam surface of the cam on the other shaft 25 allows the arm end to approach the axis of the latter shaft. In the illustrated construction best shown in Fig. 2, the cams which open the valves are generally pear-shaped in form and the cams which close the valves and cooperate with the 30 first mentioned cams are essentially circular in outline with a portion removed therefrom.

Referring now to the manifold structure 78 which is best shown in Figs. 1, 2 and 6, this structure is in the form of a ring-like or arcuate casting having an outer continuous intake gas manifold 101 and, where the engine is water cooled and not air cooled, the manifold structure 78 is also formed with a unitary inner continuous ring-like or arcuate water distributing manifold 40 45 or ring 108. The intake manifold 101 and the water distributing manifold 108 are separated from each other by a common dividing wall 109 and opposite each of the cylinders the manifold structure 78 is provided with a pair of bosses 110 45 best shown in Figs. 1 and 2 for securely mounting the manifold structure to the engine.

At uniformly spaced intervals around the intake manifold 101, this manifold is provided with 50 rearwardly extending branch conduits 112 best shown in Figs. 10 and 12 in detail. From Figs. 2 and 6 it will be apparent that in the present embodiment of my invention I have illustrated three of these branch conduits each of which 55 terminates rearwardly in a flange 113 for attachment with a carburetor 114 (see Fig. 2) and an associated air cleaner 115. The intake manifold 101 is thus supplied at a plurality of points around the manifold with fuel mixture from the carburetors 114, the intake gases passing through the 60 branch conduits 112 to the intake manifold.

Each cylinder of the engine has its cylinder head intake gas passage 99 supplied with intake gases from the intake manifold 101 and to this 65 end the intake manifold has a plurality of circumferentially spaced rearwardly opening outlets 116 which respectively register with the passages 99.

The water distributing manifold 108 is supplied 70 with cooling water from a radiator 117 shown in Fig. 1, the radiator having an outlet 118 communicating with the flexible supply conduit or hose 119. The delivery end of the conduit 119 is connected to the flange 120 of the water dis- 75

tributing manifold whereby the cooling water from the radiator is introduced to the manifold through a passage 121 which extends through the flange 120.

5 The cooling water fills the manifold 108 and is distributed therefrom to each of the engine cylinders 11 by the outlets 122 which, as best shown in Fig. 1, respectively communicate with openings 123 leading to the jacket spaces 20 in each

10 of the cylinder heads 15.

From the cylinder head jacket spaces 20 the cooling water circulates inwardly through the passages 19 and through the cylinder jacket spaces 18^a for discharge through a passage 124

15 provided in each of the cylinder inner members 14.

Each passage 124 is in communication with a passage 125 and the passages 125 extend inwardly through the aforesaid transverse wall 43 for communication with the arcuate or annular water receiving ring 126 which lies concentrically within the water ring 108. The annular chamber 126 is also formed in the dividing wall 43 around the bearings 70 of the valve shafts 69 as shown in Fig. 1. For those cylinders which are rearwardly spaced from the wall 43, as in the case of the engine cylinder illustrated at the bottom of Fig. 1, the passage 124 thereof delivers its cooling water to the passage 125^a formed in the rearwardly extending projection 127 of the dividing wall 43.

As shown in Fig. 1 the annular chamber 126 delivers the water passed thereto from the various cylinder water jackets 18^a through a passage 128 formed in the bottom wall of the valve shaft receiving chamber 73, the water then passing through the chamber 129 of the cap 130 to the inlet of a water circulating pump 131. The pump 131 thus delivers the water under pressure back to the radiator 117 through the flexible conduit or hose 132 and the communicating radiator conduit 133, the pump 131 pulling the water from the annular chamber 126 and thereby causing the water to circulate under pressure between the radiator and the engine cylinder heads and cylinders.

Intermediate the cylinders 11 at the points where the cam actuated bell crank lever arms 83 and 86 extend outwardly beyond the manifold structure 78, this manifold structure is deflected or recessed rearwardly as shown at 134 in Fig. 8. In this manner the bell crank lever arms are designed to operate without interference from the manifold structure 78 and the amount of deflection of the manifold structure 78 is in accordance with the requisite clearance at the points of location for the aforesaid pairs of cam operated arms. Thus, more clearance will be necessary for the arms actuated by the rear pairs of cams 103 on the valve shafts 69 than will be required for the forward pairs of these cams as will be readily understood. The arrangement of these inner and outer pairs of cams, together with the portions of the manifold structure 78 which are offset to lie against the progressively offset cylinders, results in the different lengths of the sleeve shaft bearings 17 and sleeve shafts 76 and 85. The manifold is recessed at 134 where necessary to provide clearance for the arms 83 and 86.

I will next describe my novel arrangement of accessory drives as best shown in Figs. 1 and 2. In Fig. 1 it will be noted that the driving shaft 45 which is co-axial with the crankshaft 30 is provided with an extension 135 projecting for-

wardly beyond the bearing portion 47^a of the end member 26. Mounted on the shaft extension 135 and secured thereto is a hub 136 which carries the fan 137 positioned adjacent the rear of the radiator 117 for inducing air circulation through the radiator for cooling the water passed thereto from the pump 131.

The valve shafts 69 are also utilized for driving various other of the engine accessories. Thus, one of these valve shafts is provided with a spiral pinion 138 shown in Fig. 2, this pinion being adapted to drive the gears 139 and 140. The gear 139 drives a shaft 141 which extends outwardly to operate the aforesaid pump 131 while the gear 140 drives its shaft 142 which extends outwardly of the engine for driving the distributor 143. The distributor is provided with the usual ignition cables 144 which respectively lead to the spark plugs 145 (see Fig. 3) for firing the charge in each of the engine cylinders.

Another of the valve shafts 69, illustrated at the top of the valve shaft receiving chamber 73 in Fig. 1, has a forward bearing in the end member 26 and carries a gear 146 of the oil pump 147, the other cooperating gear of the oil pump 25 being designated at 148.

The oil pump 147 draws its supply of lubricating oil from the oil reservoir 149 through the intermediary of the pipe 150. As best shown in Fig. 5 the oil pump delivers the oil under pressure through a passage 151 formed in the end member 26, the passage 151 communicating with a further passage 152 also formed in the end member 26 and extending outwardly from the bushing 153 at the bearing portion 47^a. The outer end of the passage 152 is closed by a plug 154.

At its inner end the passage 152 is provided with an annular passage 155 which distributes the oil to a plurality of outwardly extending passages 156 formed in the end member 26 and respectively leading to the bearing portions 71 of the various valve shafts 69.

The drive shaft 45 has its aforesaid longitudinally extending conduit 59 formed with a forward passage portion 157 and a communicating radial passage 158 adapted to register during each revolution of the shaft with a port 159 formed in the bushing 153. In this manner it will be apparent that the oil under pressure from the pump 147 is delivered to the passage 152 and therefore to the annular distributing passage 155 whence the oil is supplied outwardly to the valve shafts 69 through the radial passages 156. A portion of the oil under pressure is also supplied through the port 159 for communication through the conduit 59 of the drive shaft 45 whence the oil is passed to the crank pin 37 for lubricating the connecting rod bearings 23 and other parts associated with the spindle 36 as hereinbefore described.

The drive shaft 45 is also provided with a radial passage 160 extending through the shaft in communication with the central conduit 59 and so located that as the drive shaft 45 rotates a portion of the lubricant will be thrown under pressure or sprayed toward the cams 103 for efficiently lubricating the cams and the inner ends of the bell crank lever arms 83 and 86 which are operated by these cams.

The lubricating oil supplied to the bushing 153 serves to lubricate the forward bearing of the drive shaft 45 and the forward bearing of the valve shaft 69 which drives the oil pump 147 is lubricated as shown in Figs. 1 and 5. Thus,

this valve shaft is provided with an axial passage 161 and a radial communicating passage 162 adapted to register during each revolution of the valve shaft with a port 163 formed in the 5 bushing 164, this port opening to the passage 152. The lubricating oil thus supplied to the valve shaft passage 161 passes rearwardly therethrough to the space provided at the end of the bearing portion 70 of the valve shaft for contact 10 with the bearing portions of the bushing 165. The space at the rear of the valve shaft bearing portion 70 is closed to the crankcase 24 by a plug 166.

Each of the remaining valve shafts 69 is provided 15 with a similar radial passage 162 adapted to register with a similar port 163 of the associated forward bushing 164, each port 163 being in communication with one of the aforesaid passages 156 whereby lubricating oil is periodically supplied 20 to the various axial passages 161 for lubricating the rear bearings of the valve shafts in the manner just previously described in connection with the valve shaft which mounts the oil pump 147.

25 I have also provided means for returning the lubricating oil which is collected at the bottom of the crankcase 24 and the valve shaft receiving chamber 73 and returning this oil to the lubricant reservoir 147. Thus, as shown in Fig. 1, 30 the bottom of the crankcase 24 surrounding one or more of the inner sleeves 12 provides a collector chamber for the lubricant, the oil running off from this chamber through a pipe 167 which leads to the reservoir 149. The oil is also drained 35 from the chamber 73 by a similar pipe 168 which likewise communicates with the reservoir 149.

Various modifications and changes will be apparent from the teachings of my invention, as set forth in the appended claims, and it is not 40 my intention to limit my invention to the particular details of construction and operation shown and described for illustrative purposes.

What I claim is:

1. In an engine having a crankshaft and a plurality of cylinders radially positioned with respect to said crankshaft, each of said cylinders having an intake and an exhaust valve, a plurality of valve operating shafts, means for driving said shafts from said crankshaft, valve operating 45 means operably connected to the intake valve of each cylinder, valve operating means operably connected to the exhaust valve of each cylinder, the valve operating means for the intake valve and exhaust valve of each pair of adjacent cylinders each including one of a pair of operating 50 elements, means for positioning each pair of operating elements for actuation by a pair of said shafts, and means carried by said shafts for operating said elements.

60 2. In an engine having a crankshaft and a plurality of cylinders radially positioned with respect to said crankshaft, each of said cylinders having an intake and an exhaust valve, a plurality of cam shafts having their axes parallel to the 65 crankshaft axis, means for driving said shafts from said crankshaft, and a pair of bell crank levers each having one arm thereof positioned for actuation by a pair of adjacent cam shafts, said bell crank levers having their other arms extending 70 in generally opposite directions for respectively operating the intake valve and exhaust valve of adjacent cylinders.

75 3. In an engine having a crankshaft and a cantilever crank pin carried thereby, said crank pin having a lubricant conducting bore, a drive

shaft co-axial with said crankshaft, said drive shaft having a lubricant conducting bore, means for drivingly connecting said crank pin to said drive shaft, a plurality of cam-carrying valveshafts spaced about said drive shaft and adapted 5 to be driven therefrom, said valveshafts having their axes parallel with the axis of said drive shaft, means for supplying lubricant to said drive shaft bore, means for distributing the lubricant from said drive shaft bore to lubricate the valveshaft cams, and means for conducting lubricant from said drive shaft bore through said driving connection to said crank pin bore.

4. In an engine having a rotating cantilever driving crank, a cylindrical element connected 15 with said crank eccentrically with respect to the axis of said cylindrical element, a member drivably mounting said cylindrical element, said member driving crank, cylindrical element, and driven member being provided with communicating lubricant supplying passages, and means for conducting lubricant to one of said passages.

5. In an engine having a crankshaft, a drive shaft aligned with said crankshaft and driven 25 therefrom, a plurality of valveshafts spaced about said drive shaft and having their axes parallel with the axis of said drive shaft, cams on said valveshafts, cam followers actuated by said cams, said drive shaft having a lubricant conducting 30 bore and lubricant discharge passage communicating with said bore and adapted to spray lubricant on said cams and followers during rotation of said drive shaft, and means for supplying lubricant to said drive shaft.

35 6. In an engine of the radial type having a crankcase structure provided with an opening at one end thereof, a cover for said opening, a plurality of rotatable valveshafts journaled by said cover, an oil pump carried by said cover, said 40 cover having a plurality of oil conducting passages for conducting oil from said pump to said valveshafts.

45 7. In an engine of the radial type having a crankcase structure provided with an opening at one end thereof, a cover for said opening, a plurality of rotatable valveshafts journaled at one of their ends by said cover, said crankcase structure having a wall journaling the other ends of said valveshafts, said valveshafts having lubricant conduits axially therethrough for conducting lubricant to said wall journals, said cover having a plurality of lubricant passages for conducting lubricant to the bores of said valveshafts, and means for supplying lubricant under pressure 55 to said passages.

8. In an internal combustion engine of the radial type, a crankcase structure, a drive shaft, spaced wall structures journaling said drive shaft, a plurality of valveshafts spaced around said drive 60 shaft, journaled by said wall structures and driven from said drive shaft, one of said wall structures having a plurality of passages between said drive shaft and said valveshafts, means for supplying lubricant under pressure to one of said passages, 65 and means for conducting the lubricant from said lubricant supplied passage to the remainder of said passages for travel therethrough to said valveshafts.

9. In an engine having a plurality of radially arranged cylinders, a crankshaft, a crankcase for said crankshaft, a valve operating chamber adjacent said crankcase, a plurality of valveshafts operating in said chamber, partition means intermediate said chamber and crankcase adapted to 70 75

intercept lubricant travel from said chamber to said crankcase, means for pumping lubricant to said chamber for supply to said valveshafts and to said crankcase for supply to said crankshaft, and means for withdrawing lubricant tending to collect in said crankcase and chamber.

10. In an engine having a crankshaft and a plurality of cylinders radially disposed about said crankshaft, valving means associated with each of said cylinders, a plurality of valve operating shafts having their axes parallel to the crankshaft axis, means for driving said shafts from said crankshaft, and means for operating said valving means including a plurality of grouped pairs of elements, means for positioning the elements of each group for operation by a pair of said shafts, and means operably connecting the elements of each pair respectively with valving means of a pair of said cylinders.

20. 11. In an engine having a crankshaft and a plurality of cylinders radially disposed about said crankshaft, valving means associated with each of said cylinders, a plurality of valve operating shafts equal in number to the number of said cylinders and having their axes parallel to the crankshaft axis, cams carried by each of said shafts, means for driving said shafts from said crankshaft, means for operating said valving means including a plurality of grouped pairs of cam followers, the followers of each group being positioned for operation by cams on a pair of said shafts, and means operably connecting the followers of each pair respectively with valving means of a pair of adjacent cylinders.

35. 12. In an internal combustion engine having a crankshaft and a plurality of cylinders, a plurality of valve operating shafts each carrying a plurality of cams more than two in number, means for driving said shafts from said crankshaft, valving means for said cylinders, means for operating said valving means including a plurality of pairs of cam followers, each pair being adapted for operation by an associated pair of valve operating shafts, and means operably connecting the cam followers of each pair respectively with valving means of an adjacent pair of cylinders, each cam follower of each of said pairs having a cam operated portion positioned between

and operated by a pair of cams carried by a pair of valve operating shafts associated therewith, at least one of the cams carried by the valve operating shafts of each of said associated pairs cooperating with a cam carried by another of said valve operating shafts for operating a cam follower of another of said pairs.

13. In an engine having a crankshaft and a plurality of cylinders radially positioned with respect to said crankshaft, each of said cylinders having intake and exhaust valves associated therewith, a plurality of cam shafts the same in number as the number of said cylinders, said cam shafts having their axes parallel with the crankshaft axis, means for driving said cam shafts in unison from said crankshaft, a plurality of cams carried by each of said cam shafts, a plurality of pairs of bell crank levers, means for mounting said pairs of levers for oscillatory movement about common axes, each lever of said pairs of levers having an arm extending generally radially inwardly from the mounting thereof for operation by cams on adjacent shafts to positively operate said inwardly extending arms, each lever of said pairs of levers having an arm extending generally laterally from the mounting thereof for positively operating one of said valves, said laterally extending arms of each lever of said pairs of levers extending in generally opposite directions from the mounting thereof.

14. In an engine having a plurality of radially arranged cylinders, a crankshaft, a crankcase for said crankshaft, a valve operating chamber adjacent said crankcase, a plurality of valve operating shafts operating in said chamber, partition means intermediate said chamber and crankcase adapted to intercept lubricant travel from said chamber to said crankcase, means for supplying lubricant under pressure to said crankshaft and to said valve operating shafts, a reservoir below said chamber and crankcase adapted to receive lubricant tending to collect in said chamber and crankcase, means establishing communication between said reservoir and said chamber and crankcase, and means providing passage of lubricant from said reservoir to said lubricant pressure supply means.

ROGER K. LEE.
